(57) **CLAIM**

The ornamental design for an outdoor pole, as shown and described.

DESCRIPTION

FIG. 1 is a front, left perspective view of an outside pole according to my new design;

FIG. 2 is a front view thereof;

FIG. 3 is a left side view thereof;

FIG. 4 is a top view thereof;

FIG. 5 is a right side view thereof; and,

FIG. 6 is a rear view thereof.

The broken line portion of the figure drawings is included to show the unclaimed subject matter only and forms no part of the claimed design.
